UNITED STATES PATENT OFFICE.

ANTHONY DANIELS, OF NEWARK, NEW JERSEY, ASSIGNOR TO THE PERFEX PRODUCTS CORPORATION, A CORPORATION OF NEW JERSEY.

MACHINE FOR SEALING CONTAINERS.

Application filed April 9, 1924. Serial No. 705,187.

To all whom it may concern:

Be it known that ANTHONY DANIELS, citizen of the United States, residing at Newark, in the county of Essex and State 5 of New Jersey, has invented certain new and useful Improvements in Machines for Sealing Containers, of which the following is a specification.

This invention relates to improvements in 10 means for sealing containers. More particularly, it is directed to apparatus for effecting a closure on the ends of flexible tube receptacles such as are in common use for holding fluid or plastic materials like dental 15 cream, soap, paints, medicinal preparations and the like.

An object of the invention is to provide a 20 machine of the character described which shall operate to feed a metallic strip or ribbon through the machine to form a clip therefor and to effect with said clip an improved positive closure for tubes of the character described in a simple and highly efficient manner.

25 A further object is to provide an apparatus or mechanism of the character described which shall be adapted for use alike with tubes made of inelastic metallic alloys composed of lead, tin, and the like, as well 30 as tubes made of celluloid compounds or the like material, which are neither sufficiently plastic to stay folded when the sides of the tube are pressed together and the bottom edge folded in to form a seal, nor suitable 35 to hold a clip over such seal by pressing same into the material of the tube.

Other objects of this invention will in 40 part be obvious and in part hereinafter pointed out.

45 The invention accordingly consists in the features of construction, combinations of elements and arrangement of parts which will be exemplified in the construction hereinafter described and of which the scope of application will be indicated in the following claims.

In the accompanying drawing, in which is shown one of the various possible illustrative embodiments of this invention,

50 Fig. 1 is a plan view of the main portion of a clip forming and sealing apparatus embodying my invention with the plunger broken away to show the arrangement and means for feeding, forming and clinching the strip;

Fig. 2 is a fragmentary view in front elevation of that shown in Fig. 1;

Fig. 3 is a view in side elevation of that shown in Fig. 2;

Fig. 4 is a sectional view taken on line 60 4-4 of Fig. 2 showing portions of the strip punching arrangement;

Fig. 5 is a sectional view taken on line 65 5-5 of Fig. 1 showing portions of the strip feeding mechanism;

Fig. 6 is an enlarged view in side elevation of a fragmentary portion of the apparatus illustrated in Fig. 3 showing the clamping means in released position and the plunger finishing the folding operation to 70 seal the tube end;

Fig. 7 is a sectional view taken on line 75 7-7 of Fig. 1 showing portions of the clip forming means; and

Fig. 8 is a fragmentary plan view of that 75 portion of the machine shown in Fig. 1 showing the arrangement of parts effective for feeding the strip.

Referring to the drawing, the embodiment of the invention therein illustrated 80 comprises a base-frame 10 having an upstanding portion 11, the upper right hand end thereof forming a front bearing 12 for a main drive-shaft 13, the rear end thereof being supported in bearing 14 formed on 85 the upper end of the upright member 15, which is rigidly mounted on or may be formed integral with frame 10. Shaft 13 may be driven by any suitable source of power, not shown, through well-known 90 means, as for example by a pulley 17 and a disconnecting clutch 18 mounted on the rear end of said shaft.

A beveled gear 19 is fastened to shaft 13 and meshes with a similar gear 20 secured 95 on the upper end of a vertically extending driven-shaft 21 supported in a bearing 22 on the rear side of the upstanding portion 11 of frame 13, as shown in Fig. 3. Another beveled gear 40 is rigidly mounted on shaft 100 21 and meshes with a similar gear 41 secured to the end of a horizontal counter-shaft 42 supported in bearings 43 and 44 projecting up from the base 10. (See Figs. 1 and 4.)

Rigidly mounted on the front free end of shaft 13 is a cam 23 which is effective on 105 rotating of said shaft to slide a plunger member 24 vertically downward in a guide way cut in said portion 11 against the normal upward pressure of spring 25 set be- 110

tween the under side of plunger 23 and base 10 as shown in Fig. 3. Forwardly extending from the lower portion of plunger 23 is an elongated pressure-head support 26 having a downwardly projecting pressure member 27 hinged on the lower side of the right hand end, and a groove 27^a may be formed on the bottom side of the latter. The hinged mounting of the pressure member, the purpose of which will hereinafter appear, permits a slight movement with respect to support 26 limited by a screw 50 which passes through the free rear end portion of member 27 and is threaded into support 26. A compression spring 51 may be provided between the support 26 and member 27 as an additional means for urging the latter to its downward position. (See Figs. 3 and 6.) A fixed supporting ledge 28 formed from a forwardly projecting portion of base 10 extends under support 26 and is cut away at 29 under pressure member 27, for insertion of the end portion of a tube 30 into a closure clip 31 held between groove 27^a and a groove 28^a in the outer portion of ledge 28. The clip 31 is preferably J or hooked shaped having legs 31^a and 31^b of unequal length, the former being the longer. Said clip 31 fits with its bent portion in groove 27^a and the free end of leg 31^a in groove 28^a as shown in Fig. 3.

An outer clamping jaw of ejecting piece 32 is mounted and guided on ledge 28 for sliding movement and is operated through a linkage comprising a lever 33 pivoted at 34, connecting link 35 and a cam member 36 pivoted at 37 from the rear side of upright portion. Member 36 has a projection 36^a on the side thereof which rides on cam 38 fast on counter shaft 42. Figs. 1, 2, 3, and 5 plainly show the means whereby the rotation of cam 38 on shaft 42 will cause the linkage to slide jaw 32 rearward and coil springs 39 and 39^a may furnish means for return movement.

An inner clamping jaw 45 may have a push bar 46 extending rearwardly thereof passing through upright portion 11 and may be urged rearwardly by tension spring 47, one end thereof being fastened to the free end of bar 46, and the other anchored to base 10. A pivoted bearing piece 48 is interposed between bar 45 and a cam 49 rigidly mounted on shaft 21. Figs. 1 and 3 plainly show the means whereby the rotation of a cam 49 will cause jaw 45 to slide forward spring 47 being effective to provide return movement. An adjusting screw 50 threaded into the end of piece 48 and bearing on the rear side of bar 46 may be provided for adjusting the jaw 45 in proper position.

The closure operation may now be described. Let it be assumed that the machine parts are in the position shown in Fig. 3. The end portion of a tube 30 with its sides

pressed together is inserted up into the bend of clip 31. Drive shaft 13 through gears 19 and 20 will rotate shaft 21 with cam 49 and through gears 40 and 41 will also rotate counter shaft 42 with cam 37. Cam 49 will force the inner clamping jaw 45 forward to firmly clinch the end portion of tube 30 between legs 31^b and 31^a of clip 31. The outer jaw 32 has a V-shaped surface 32^a against which leg 31^a of clip 31 bears which causes the clip 31 and the end portion of the tube 30 to be bent during the clinching operation to conform with the shape of the surface 32^a as a result of the pressure exerted by the co-acting surface 45^a on inner jaw 45. Further rotation of shafts 31, 21 and 42 releases jaws 32 and 45 from the action of cams 37 and 49 respectively, and permits springs 39 and 39^a to slide jaw 32 forward and spring 47 to slide bar 46 with jaw 45 rearwardly away from clip 31 and tube 26 which is meanwhile supported in grooves 27^a and 28^a.

The hinged mounting arrangement of pressure member 27 hereinbefore described permits movement of groove 27^a to hold clip 31 during and after the above described bending operation thereof.

As soon as clamping jaws 32 and 45 have been moved from under pressure member 27, the cam 23 on shaft 13 is arranged to force plunger 24 down to fold the clinched and bent portion of clip 31 and the end portion of tube 30 to form a seam as shown in Fig. 6. Further rotation of shafts 13, 21, and 42 releases plunger 19 from the action of cam 23 and permits the spring 25 to return the plunger 24 and pressure member 27 to their initial position as shown in Fig. 3. The upward movement of member 27 is followed by a forward movement of jaw 32 to its initial position thus ejecting the finished tube 30. The cut away portion 29 of ledge 28 may be shaped as shown in Fig. 3 to allow free passage of the tube 30 when ejected.

A new clip is now inserted in grooves 27^a and 28^a and the operation repeated. To automatically accomplish this the invention also provides means for automatically feeding a metallic strip or ribbon 51 through the machine for forming clip 31 from said strip 51 and for advancing the clip 31 into the grooves 27^a and 28^a to complete the closure on the end portion of the tube 30.

The feeding means may include an oscillating member 52 on which strip 51 is carried and adjustably mounted on the left hand end thereof a cross head 53. A screw 54 permits longitudinal adjustment of the cross head 53 along member 52 and screw 55 passing upwardly through a slotted recess 55^a in the bottom of member 52 is threaded into a cross-head 53 for securely

fastening same in position. A rod 56 connects cross head 53 with a crank disc 57 which is mounted to rotate with a shaft 58 supported in bearings 59 and 60 as shown in Fig. 1. A bevel gear 61 on the end of counter shaft 42 meshes with a similar gear 62 for turning shaft 58, and thereby supplying means for oscillating member 52. Shaft 42 also carries at about its mid-length a bevel gear 63 which meshes with another gear 64, the latter being mounted on a short shaft journaled in upright member 11. Shaft 65 has secured on its forward end a cam 66 for controlling the feeding of strip 51 as will be explained. The left hand portion of ledge 28 is grooved for member 52 to slide therein and carries a follower piece 67 rearward thereof on which a cam plate 68 is mounted for limited movement by slot 69 and screw means 69 as shown in Figs. 1, 5 and 8. Cam 66 is arranged to be engaged by projections 68^a and 68^b on cam plate 68 and the right hand end thereof co-operates with a roller 70 for effecting the feeding of strip 51.

Assuming that the position of the parts of the feeding means are as shown in Fig. 1, the roller 70, resting on the rearwardly extending portion of the right hand end of plate 68, holds the spring 71 of a feed-clamp 72 in compression and free from the edge of strip 51. On rotation of the shafts, member 52 is moved to the left carrying follower piece 67, cam plate 68, roller 70, and feed clamp 72 therewith, while strip 51 which is supported on member 52 remains relatively at rest. When the stroke of member 52 to the left is completed the cam 66 will engage projection 68^b of cam plate 68 and slide the same with respect to roller 70 so as to release the clamp 72 for side-gripping strip 51 between it and an adjustable overlying guide plate 73 fastened to member 52 by screws 74. (See Figs. 1, 5 and 8.) The next stroke of member 52, which is to the right will carry the strip 51 therewith. In the completion of this latter movement, cam 66 will engage projection 68^a and slide cam plate 68 back to its initial position as shown in Fig. 1. This feeding operation is continuously repeated during the operation of the machine and advances strip 51, the length of one clip for each movement to the right of member 52.

The clip forming means may include a side-edge notcher 75, and a severing and strapping mechanism 76, the former consisting of a die guiding plate 77 secured to ledge 28 in alignment with punch members 78 mounted on the left hand end of pressure head support 26, and a die 79 supported from edge 28 in a slotted section in member 52 as shown in Fig. 4. Notcher 75 serves to cut out spaced portions from strip 51 which latter forms desired rounded edges

on the clip 31. Mechanism 76 (see Fig. 7) comprises an outer clip shaping member 80 which preferably may be yieldingly mounted on the bottom side of support 26 between the punch 78 and pressure member 27, and an inner shaping member 81 corresponding to member 80 firmly secured to ledge 28. Member 80 may have a spring pressed rod passing therethrough for holding the strip 52 against movement on member 81 while it is being shaped into a clip.

Mechanism 76 also provides means for severing strip 52 during the stamping operation by arranging the left hand sloping edges of member 80 and a fixed cutting edge 83 under a guide plate 84 to act as shearing means. (See Figs. 1 and 7.) The shaping member 81 is arranged to guide the clip 31 as it is advanced into grooves 27^a and 28^a of the tube end closure mechanism.

The continuous sequence of strip feeding, clip forming, and closure operations take place as follows: With the parts positioned as shown in Fig. 1 and a clip 31 held in grooves 27^a and 28^a between jaws 32 and 46 as shown in Fig. 3, the end portion of a tube 31 with its sides pressed together is inserted up in the bend of the clip and member 52 with clamp 72 is caused to move to the left on the rotation of the driving shafts. Cam 49 on shaft 21 next becomes effective to drive jaw 46 forward for clamping the tube end and clip together and bending the clenched portion, and then cam 49 and cam 37 on shaft 42 act to withdraw jaws 32 and 46 respectively from under pressure member 27. Cam 23 on shaft 13 by this time is in position to force plunger 24 downward and since punch 78 of notcher 75, shaping member 80 of mechanism 76, and pressure member 27 are all carried by support 26 of plunger 24, the descending movement of the latter results in simultaneously punching the edge portion of the strip severing and forming the clip and completing the closure operation by folding the bent portion of the tube end to form a seam. A short interval after plunger 24 has finished its working stroke to allow it to be returned to its initial position and thereby raise pressure member 27 clear of the path of movement of jaw 32, cam 37 becomes effective to move jaw 32 rearward ejecting the completed tube. In the meantime member 52 has traveled its entire return stroke and is moving to the right with clamp 72 gripping strip 51 as a result of cam 66 acting on projection 68^b of cam plate 68, as has been described above.

As strip 51 advances, it feeds the clip 31 formed in mechanism 76 into grooves 27^a and 28^a and positions the leading portion of the strip 51 for repeating the cycle of operation.

Briefly the arrangement and combination of parts are such that a metallic strip sup-

plied to the machine is automatically fed therethrough, a clip formed thereby and said clip clamped over the end portion of a tube, bent and folded to form a seamed closure, the tube ejected, and another clip positioned in proper sequence for continuous operation.

It will thus be seen that there is provided a device in which the several objects of this invention are achieved and which is well adapted to meet the conditions of practical use.

As various possible embodiments might be made of the above invention and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. A machine for effecting a closure of a tube end comprising means for cutting and shaping a clip from a metallic strip fed to the machine co-operatively connected for continuous operation with means for clamping the clip over the tube end, and for infolding the clinched clip and tube end portions to form a seam.

2. A machine for effecting a closure of a tube end comprising means for cutting and shaping a clip from a metallic strip fed to the machine co-operatively connected for continuous operation with means for clamping the clip over the tube end, and for infolding the clinched clip and tube end portions to form a seam, parts of said clamping means serving to eject the tube after completing the closure.

3. A machine for effecting a closure of a tube end comprising means for cutting and shaping a clip from a metallic strip fed to the machine, and means for clamping the clip over the tube end, and for infolding the clinched clip and tube end portions to form a seam, portions of said clamping and infolding means serving to guide and position the clips in the machine.

4. A machine for sealing a tube end with a clip comprising two movable members for clamping the clip to the tube end and for bending the clinched portion preparatory to folding thereof, and means for folding the bent clinched portion to form a seam, said means comprising a plunger support and a hinged pressure-head mounted thereon to co-act with a relatively fixed part of the machine for forming the said seam.

5. A machine for sealing a tube end with a clip comprising two movable members for clamping the clip to the tube end and for bending the clinched portion preparatory to folding thereof, and means for folding the bent clinched portion to form a seam, said means comprising a plunger support and a

hinged pressure-head mounted thereon to co-act with a relatively fixed part of the machine for forming the said seam, and means arranged to eject the tube after completing the closure by one of said movable members.

6. A machine for sealing a tube end with a clip comprising two movable members for clamping the clip to the tube end and for bending the clinched portion preparatory to folding thereof, and means for folding the bent clinched portion to form a seam, said means comprising a plunger support and a hinged pressure-head mounted thereon to co-act with a relatively fixed part of the machine for forming the said seam, said head and said machine part having grooves therein for holding the clip in place for the sealing operation.

7. A machine for sealing a tube end with a clip comprising two movable members for clamping the clip to the tube end and for bending the clinched portion preparatory to folding thereof, and means for folding the bent clinched portion to form a seam, said means comprising a plunger support and a hinged pressure-head mounted thereon to co-act with a relatively fixed part of the machine for forming the said seam, said head and said machine part having grooves therein for holding the clip in place for the sealing operation, means for cutting and shaping the clip from the leading end of a strip fed to the machine during the closure operation, and means for advancing the clip to the clamping and folding means in proper sequence and position for continuous operation.

8. A machine for effecting a closure on a tube end with a clip comprising means for clamping the clip over the tube end and for folding the clinched clip and tube end portion to form a seam, means for feeding a strip through the machine, means for cutting and shaping a clip from the leading end of the strip during the closure operation and means for advancing the clip to the clamping and folding means in sequence and position for continuous operation, said feeding means comprising an oscillating member over which the strip passes and a clamping means mounted on said member intermittently effective to secure the strip to the said member for movement therewith.

9. A machine for effecting a closure on a tube end with a clip comprising means for clamping the clip over the tube end and for folding the clinched clip and tube end portion to form a seam, means for feeding a strip through the machine, means for cutting and shaping a clip from the leading end of the strip during the closure operation and means for advancing the clip to the clamping and folding means in sequence and position for continuous opera-

tion, said feeding means comprising an oscillating member over which the strip passes and a clamping means mounted on said member intermittently effective to secure the strip to the said member for movement therewith, and means for controlling the movable machine elements to permit continuous operation.

10. A machine for sealing a tube end comprising a stamping and severing means for forming a substantially J-shaped clip from a metallic strip fed to the machine co-operatively connected for continuous operation with means for clamping the clip over the tube end and for infolding the clinched portions of the clip and tube end to form a seal.

11. A machine for sealing a tube end comprising a stamping and severing means for forming a substantially J-shaped clip from a metallic strip fed to the machine co-operatively connected for continuous operation with means for clamping the clip over the tube end and for infolding the clinched portions of the clip and tube end to form a seal, parts of said clamping means serving to eject the tube after completing the closure.

12. A machine for sealing a tube end comprising a stamping and severing means for forming a substantially J-shaped clip from a metallic strip fed to the machine, and means for clamping the clip over the tube end and for making a fold in the clinched portion, said means comprising two movable members and a plunger support having a hinged pressure head mounted thereon to co-act with a relatively fixed part of the machine.

13. A machine for sealing a tube end comprising a stamping and severing means for forming a substantially J-shaped clip from a metallic strip fed to the machine, and means for clamping the clip over the tube end and for making a fold in the clinched portion, said means comprising two movable members and a plunger support having a hinged pressure head mounted thereon to co-act with a relatively fixed part of the machine, and means arranged to eject the tube after completing the closure by one of said movable members.

14. A machine for sealing a tube end comprising a stamping and severing means for forming a substantially J-shaped clip from a metallic strip fed to the machine, and means for clamping the clip over the tube end and for making a fold in the clinched

portion, said means comprising two movable members and a plunger support having a hinged pressure head mounted thereon to co-act with a relatively fixed part of the machine, the head and said machine part having grooves therein for holding the clip in place with the bend of the clip in the head groove and the free end of the longer side 65 of the clip in the machine part groove.

15. In a machine for sealing tube ends having means for forming a clip from a metallic strip, means for feeding the strip through the machine comprising an oscillating member over which the strip passes, and a clamping means mounted on said member intermittently effective to secure the strip to the said member for feeding movement therewith.

16. A machine for sealing tube ends comprising means for feeding a metallic strip through the machine, a notcher for punching the edge portions of the strip, a shaping and severing mechanism for forming a clip, 80 means for effecting a folded closure with said clip and means for controlling the movable machine elements to permit continuous operation.

17. A method for effecting a closure on a tube end comprising the bending of a flat metallic strip transverse the length thereof to form a substantially J-shaped clip having legs of unequal length, pressing together the sides of the end portion of the tube to be 90 closed, inserting the said end portion up into the bend of the clip and clamping the same between the legs thereof, and folding the clinched portion transverse the length of the clip substantially in line with the free 95 end of the shorter leg so that the longer leg of said clip forms the outer side and the shorter leg the inner fold of a closure seam for the tube end.

18. A machine for effecting a closure of 100 a tube end with a clip comprising means for clinching the clip to the tube end and for infolding the clinched tube end portion to form a seam, said means having co-operatively connecting for continuous operation 105 therewith means for cutting and shaping the clips from a strip of material fed to the machine, all operating parts of the first mentioned means positioned to effect the complete closure operation while the tube is 110 in a relatively fixed position.

In testimony whereof I affix my signature.

ANTHONY DANIELS.
